CIRCUIT FOR THE AMPLIFICATION AND/OR FREQUENCY-TRANSFORMATION OF ELECTRICAL OSCILLATIONS OF ULTRA HIGH FREQUENCY

Gerrit Hendrik Petrus Alma, Maximiliaan Julius Otto Strutt, and Aldert van der Ziel, Eindhoven, Netherlands; vested in the Alien Property Custodian

Application May 9, 1941, Serial No. 392,633
In the Netherlands June 12, 1940

18 Claims. (Cl. 179—171)

This invention relates to a circuit arrangement for the amplification and/or frequency-transformation of electrical oscillations of ultra-high frequency, and to a discharge tube adapted to be used in such a circuit.

With ultra-high frequencies a virtual ohmic resistance of comparatively low value generally occurs intermediate the control grid and the cathode of a discharge tube, said resistance bringing about a considerable damping of the input circuit. The occurrence of this virtual ohmic resistance is principally to be attributed to two causes. In the first place the inductances of the supply conductors to the various electrodes constitute rather appreciable impedances for ultra-high frequencies. High-frequency voltages occur across these impedances and give rise to currents through the capacities of the tube. Thus, the alternating current of the cathode will generally bring about a voltage across the inductance of the cathode supply-conductor, which voltage leads 90° relatively to the alternating voltage of the control grid. This voltage brings about a current from the control grid to the cathode via the control grid-cathode capacity, which current is in phase with the alternating voltage of the control grid and may consequently be regarded as a result of an ohmic resistance existing between the control grid and the cathode. Similar currents flow from the control grid via the capacities of the tube to other electrodes. The resulting total damping of the input circuit is referred to as conductor damping.

It is known to decrease the conductor damping by using a tube whose cathode is provided with two separate supply conductors, one of these supply conductors being included in the input circuit and the other in the output circuit. In this case the voltage brought about by the output current across the cathode supply-conductor included in the output circuit is not active in the input circuit and consequently cannot bring about damping of the input circuit.

In the second place, with ultra-high frequencies the transit time of electrons is of the same order of magnitude as the cycle of the oscillations to be amplified, so that a rather appreciable phase-displacement may occur between the electron current flowing through the apertures of the control grid and the alternating voltage of the control grid. Due to this phase-displacement, an influence current flows from the control grid to the cathode, which current comprises a component which is in phase with the alternating voltage of the control grid and may therefore

be regarded as a result of an ohmic resistance existing between the control grid and the cathode. The reciprocal value of this ohmic resistance is referred to as transit-time damping or electron damping.

It has been found as will be explained hereinafter that the electron damping which occurs between the control grid and the cathode may be considerably reduced and under certain conditions be made even negative by the use of a circuit in which a grid of positive polarisation voltage is provided intermediate the control grid and the cathode.

For a better understanding of the invention, reference will be had to the accompanying drawing in which Fig. 1 discloses a circuit which utilizes a tube having a space charge or suction grid whereby the electron damping occurring between control grid and cathode may be reduced; Figs. 2 to 6 disclose various circuits which embody the invention of the present application and which are improvements over the circuit of Fig. 1; Fig. 8 shows the manner of converting the circuits of Figs. 2 to 6 to frequency-changing stages; and Fig. 7 shows a preferred form of construction and electrode arrangement of a discharge tube utilized in the circuit of Figs. 2 to 6.

Referring first to Fig. 1 the discharge tube is shown to comprise a cathode 2, a control grid 3, a screen grid 4 and an anode 5. Intermediate the control grid 3 and the cathode 2 there is connected an input impedance 6 and between the anode 5 and the cathode 2 an output impedance 7. Further, the tube comprises a grid 8 between the control grid 3 and the cathode 2, said grid being connected to the cathode 2 via a condenser 9, which practically constitutes a short-circuit for the frequency of the oscillations to be amplified and having a positive polarisation voltage supplied to it via a resistance 10. Such a positive grid intermediate the control grid and the cathode is usually indicated as space-charge grid or suction grid. The electron damping produced between the control grid 3 and the cathode 2 is considerably less than with a tube without a suction grid and may be even negative with a correct choice of the polarisation voltages of the electrodes.

The occurrence of negative electron damping between the control grid and the cathode in a discharge tube comprising a suction grid may probably be explained as follows. When the control grid 3 has a great negative bias, all the electrons passed by the suction grid 8 will reverse their direction in the vicinity of the control grid

and flow again to the suction grid. The electrons which reverse their direction constitute a space-charge in the vicinity of the control grid, inducing an equal positive image charge on the control grid. If, now, the control grid is made less negative, part of the electrons will be passed by the control grid. Consequently, the said space charge is reduced, resulting also in a decrease of the positive image-charge accumulated in the control grid so that there is a range of biases of the control grid within which the charge of the control grid becomes less positive when the bias is made more positive. In other words, in this range the control grid has a negative capacity relatively to the cathode. In this case an alternating voltage set up between the control grid and the cathode will bring about a current from the control grid to the cathode which lags 90° relatively to the said alternating voltage. This current is transferred by the electrons flowing from the cathode to the space charge. Now, with ultra-high frequencies the transit-time of these electrons is of the same order of magnitude as the cycle of the oscillations to be amplified. The transfer of the said current will consequently be effected with an appreciable time-lag, which means that the current will lag more than 90° relatively to the alternating voltage of the control grid and consequently comprise a component which is in anti-phase with the alternating voltage of the control grid. This component may be regarded as a result of a negative ohmic resistance produced between the control grid and the cathode.

Due to the small or negative electron damping, the resulting input damping in a discharge tube having a suction grid is considerably smaller than in the usual discharge tubes so that it is particularly adapted for the amplification of oscillations of ultra-high frequency.

The invention has for its purpose further to decrease the input damping in a circuit arrangement for the amplification and/or the frequency-transformation of electric oscillations of ultra-high frequency, in which use is made of a discharge tube having a suction grid.

According to the invention, this object is achieved by providing the suction grid with two separate supply conductors, the suction grid being connected for high-frequency via one of these supply conductors to the control grid and via the other supply conductor to the output electrode.

The invention is based on recognition of the fact that in a discharge tube having a suction grid the conductor damping produced between the control grid and the cathode is principally brought about by the inductance of the supply conductor to the suction grid. This may be explained as follows by reference to Fig. 1.

The electron current emitted by the cathode 2 is always exclusively determined by the voltage of the suction grid 3. Since the suction grid is connected for high frequency via a minimum impedance to the cathode, the cathode current, if taken roughly, will be constant. This constant electron current is divided by the control grid 3 into two parts, viz. one part which flows through the apertures of the control grid to the anode 5 and another part which inverts its direction and is collected by the suction grid. If the control grid 3 is made less negative, the electron current to the anode will increase, whereas the electron current to the suction grid decreases by the same value. If, on the other hand, the control grid is made more negative the electron current

which flows to the anode decreases, whereas the electron current which flows to the suction grid increases by the same value. If an alternating voltage is set up at the control grid, alternating currents of equal value but of opposite phase will consequently flow in the anode circuit and in the circuit of the suction grid. In the part of the cathode lead which is common to the anode circuit and the circuit of the suction grid these two alternating currents neutralise each other so that no alternating current flows in this part of the cathode lead. Consequently, the alternating current of the anode does not flow from the cathode to the anode, as in the usual discharge tubes, but from the suction grid to the anode. In other words, the suction grid has taken over the function of the cathode for alternating currents of the frequency to be amplified.

The alternating current flowing from the suction grid to the anode brings about a high-frequency voltage across the inductance of the connection lead between the suction grid and the point 11 in which the anode circuit and the circuit of the suction grid come together. This voltage supplies a current through the series-connection of the input impedance 6 and the control grid-suction grid capacity indicated by 12 in the figure, which current leads approximately 90° relatively to the said voltage and is consequently in phase with the alternating voltage of the control grid. The current may be regarded to be brought about by an ohmic resistance existing between the control grid and the suction grid and bringing about a damping of the input impedance 6. Now, the invention consists in that this conductor damping is suppressed by the use of a suction grid having two separate supply conductors so that the voltage brought about by the output alternating current across the supply conductor to the suction grid is no longer active in the input circuit.

Referring now to the circuit arrangement shown in Fig. 2 which embodies one form of the present invention the suction grid 8 is provided with two separate supply conductors 13 and 14. The suction grid is connected via the supply conductor 13 and the input impedance 6 to the control grid 3 and via the other supply conductor 14 and the output impedance 7 to the anode 5. The alternating current of the anode does now produce a voltage across the inductance of the supply conductor 14, but this voltage is not active in the circuit constituted by the input impedance 6 and the control grid-suction grid capacity and consequently cannot lead to damping of the input circuit.

The suction grid 8 is connected for high-frequency via a minimum impedance to the cathode. In the circuit shown in Fig. 2 this connection is made via the supply conductor 13 from which the suction grid is also connected to the control grid.

On the other hand, in the circuit shown in Fig. 3 the suction grid is connected to the cathode via the supply conductor 14 via which the suction grid is connected to the anode. The latter circuit is in general preferable and this on the ground of the following considerations.

The cathode 2 is preferably earthed, that is to say connected to the chassis of the amplifier. The extremity of the output impedance 7 which is connected to the anode generally has a rather considerable capacity relatively to the chassis, which capacity is indicated by 15 in Figs. 2 and 3. Consequently, a component of the alternating

current of the anode will flow from the suction grid via the connection of the suction grid and the cathode and via the chassis and the capacity 15 to the anode. In the circuit shown in Fig. 2 this component flows via the supply conductor 13 and may then lead to damping of the input circuit. This inconvenience could be eliminated only by electrostatically screening the circuit 7 relatively to the chassis. On the other hand, in the circuit shown in Fig. 3 the component of the anode current in question flows via the supply conductor 14 so that no damping of the input circuit can occur and screening of the circuit 7 is redundant. These considerations are particularly of importance with cascade circuits since in these circuits the capacity 15 is also determined by the input circuit of the following stage so that this capacity cannot be completely eliminated even by screening the circuit 7. Consequently, in cascade circuits the suction grid in each stage will preferably be connected via the supply conductor 14 to the cathode.

In the circuits shown in Figs. 2 and 3 the screen grid 4 is connected via the supply conductor 14 to the suction grid. Consequently, the voltage brought about across the supply conductor 14 by the alternating current of the screen grid cannot cause damping of the input circuit. In addition, the advantage is obtained that the voltage set up across the supply conductor 14 gives rise to a current via the conductor 13, the input impedance 8 and the control grid-screen grid capacity, which current is in anti-phase with the alternating voltage of the control grid and consequently brings about a reduction of the damping of the input circuit.

If the discharge tube comprises a secondary-emission electrode, a similar damping-reduction action may be obtained by connecting the secondary-emission electrode for high-frequency to the suction grid via that supply conductor via which the suction grid is connected to the control grid. This case is represented in Fig. 4.

In the circuit according to Fig. 4 use is made of a tube comprising a secondary-emission electrode 16 which is connected for high frequency via the supply conductor 13 to the suction grid. The current of the secondary-emission electrode brings about a high-frequency voltage across the supply conductor 13 which voltage produces a current through the input impedance 8 and the control grid-suction grid capacity. Due to the fact that the current of the secondary-emission electrode is in anti-phase with the alternating voltage of the control grid of the said current flowing through the control grid-suction-grid capacity will also be in anti-phase with the alternating voltage of the control grid and consequently exert a damping-reducing action on the input circuit.

The said damping-reducing effects may, if desired, be further increased by artificially increasing the screen grid-control-grid capacity or the control grid-suction-grid capacity by connecting an additional condenser in parallel, or by providing additional inductances in series with the supply conductors of the suction grid. Of the latter case an example is given in the circuit shown in Fig. 5.

In the circuit shown in Fig. 5 additional impedances Z_1 and Z_2 are provided in series with the supply conductors 13 and 14 for the suction grid. To obtain a greater damping reduction of the input circuit, these impedances are generally made in the form of inductances. With the am-

plication of very high frequencies, during which considerable phase-displacements of the anode current or of the current of the secondary-emission electrode may occur due to the finite transit time of the electrons, these phase-displacements may, however, be taken into account with the choice of the impedances Z_1 and Z_2 with a view to obtaining the phase, required for the desired damping reduction, of the voltages which occur across these impedances and the supply conductors of the suction grid connected in series therewith. It is evident that the use of the impedance Z_2 is only effective if the current of one or more positive electrodes flows through the supply conductor 13, that is to say, for example in the case that the tube has a secondary-emission electrode.

Fig. 6 shows a circuit according to the invention in which an additional control-grid 17, connected via a circuit 18 to the cathode, is provided between the suction grid 8 and the cathode 2. This circuit may be used in two manners and this either as a frequency-changing stage or for obtaining double amplification. When used as a frequency-changing stage in a superheterodyne receiver the circuit 18 has supplied to it the oscillations f_0 locally generated while in the circuit 8 are produced the received oscillations. Due to the presence of two separate supply conductors for the grid 8, the circuit 8 is damped to a considerably less extent than in the mixing circuits hitherto used. The circuit 7 is in this case tuned to the desired intermediate-frequency f_1 .

If the circuit in question is used to obtain double amplification the circuits 8, 7 and 18 are tuned to the same frequency f_1 , the oscillations to be amplified being supplied to the circuit 18. The space charge which occurs in the vicinity of the control grid 8 and whose intensity is variable with the voltage to be amplified which is active at the control grid 17 induces in the control grid 8 a charge which varies in a similar manner and leads to the occurrence of an amplified voltage across the circuit 8. This amplified voltage now again controls the electron current flowing through the control grid 8, resulting in a double amplified voltage of frequency f_1 being produced across the circuit 7.

The circuits shown in Figs. 2, 3, 4 and 5 may be adapted as frequency-changing stages, as shown in Fig. 8 by including an impedance 20 in the circuit of the control grid 8 in series with the circuit 8, via which impedance there are impressed the oscillations locally generated by a source 21, and by tuning the circuit 7 to the desired intermediate-frequency.

Fig. 7 shows a cross-section through the electrode system of a discharge tube which is adapted to be used in the circuits shown in Figs. 2 and 3. This tube comprises a directly-heated cathode 2, a control grid 8, a screen grid 4 and an anode 5. Between the control grid 8 and the cathode 2 is provided a suction grid 8 constituted by four rods placed in parallel with the cathode. Further, the space enclosed by the control grid is divided into two parts by a certain number of rods 19 which are preferably given a negative potential relatively to the cathode and which prevent electrons which inverse their direction in the vicinity of the control grid from propagating to the other side of the cathode. According to the invention, the suction grid 8 is provided with two separate supply conductors, as is indicated diagrammatically by the dotted lines 13 and 14.

We claim:

1. A circuit for the transmission of electrical oscillations of ultra-high frequency, which comprises a discharge tube provided with at least a cathode, a control grid and an output electrode, a suction grid having a positive bias being provided intermediate the control grid and the cathode, in which circuit the suction grid is provided with two separate supply conductors, the suction grid being connected for high-frequency via one of these supply conductors to the control grid and via the other supply conductor to the output electrode.

2. A circuit as claimed in claim 1, in which the biasses of the electrodes are so chosen that a negative electron damping occurs between the control grid and the cathode.

3. A circuit as claimed in claim 1, in which the suction grid is connected to the cathode via the supply conductor, via which the suction grid is connected to the anode.

4. A circuit as claimed in claim 1, wherein the discharge tube comprises also a screen grid, the screen grid being connected to the suction grid via the supply conductor, via which the suction grid is connected to the anode.

5. A circuit as claimed in claim 1, wherein the discharge tube comprises also a secondary-emission electrode, the secondary-emission electrode being connected to the suction grid via the supply conductor, via which the suction grid is connected to the control grid.

6. A circuit as claimed in claim 1, in which an impedance is provided in series with at least one of the supply conductors of the suction grid, said impedance being of such nature that a further damping-reduction of the input circuit is obtained.

7. A circuit as claimed in claim 1, in which a second control grid is provided between the suction grid and the cathode.

8. A circuit for the transmission of electrical oscillations of ultra-high frequency, comprising a discharge tube provided in the order named with at least a cathode, a space charge grid, a signal control grid and an anode, two separate supply conductors connected to the space charge grid, means for connecting the space charge grid for high-frequency via one of said conductors to the signal control grid, and means for connecting the space charge grid for high-frequency via the other of said conductors to the anode.

9. A circuit for the amplification of electrical oscillations of ultra-high frequency, comprising a discharge tube provided in the order named with at least a cathode, a space charge grid, a signal control grid and an anode, input and output circuits connected respectively to the signal control grid and to the anode, two separate supply conductors connected to the space charge grid, means for connecting the space charge grid for high-frequency via one of said conductors and the input circuit to the signal control grid, and means for connecting the space charge grid for high-frequency via the other of said conductors and the output circuit to the anode.

10. A circuit for the amplification of electrical oscillations of ultra-high frequency, comprising a discharge tube provided in the order named with at least a cathode, a space charge grid, a signal control grid and an anode, two separate supply conductors connected to the space charge grid, means for connecting the space charge grid for high-frequency via one of said conductors to the signal control grid, means for connecting

the space charge grid for high-frequency via the other of said conductors to the anode, and means for connecting the space charge grid to the cathode via said other conductor.

5 11. A circuit as defined in claim 10 wherein the tube is provided with a screen grid, the latter being connected for high frequency to the space charge grid via the conductor which is connected to the anode and cathode.

10 12. A circuit as defined in claim 10 wherein the tube is provided with a secondary-emission electrode, the latter being connected for high frequency to the space charge grid via the conductor which is connected to the control grid.

15 13. A circuit as defined in claim 10 wherein the tube is provided with a screen grid and with a secondary-emission electrode, the former being connected for high frequency to the space charge grid via the conductor which is connected to the anode and cathode and the latter being connected for high frequency to the space charge grid via the conductor which is connected to the control grid.

20 14. A circuit as defined in claim 10 wherein an impedance is provided in series with at least one of the supply conductors of the space charge grid.

25 15. A circuit as defined in claim 10 wherein the tube is provided with a secondary-emission electrode, the latter being connected for high frequency to the space charge grid via the conductor which is connected to the control grid and wherein an impedance is connected in series with each supply conductor of the space charge grid.

30 16. A circuit for the amplification of electrical oscillations of ultra-high frequency, comprising a discharge tube provided in the order named with at least a cathode, a first signal control grid, a space charge grid, a second signal control grid and an anode, resonant circuits connected to both

35 signal control grids and to the anode, two separate supply conductors connected to the space charge grid, means for connecting the space charge grid for high-frequency via one of said conductors to the second signal control grid, means for connecting the space charge grid for high-frequency via the other of said conductors to the anode, and means for connecting the space charge grid to the cathode via said other conductor.

40 17. A circuit as defined in claim 16 wherein each of the three resonant circuits is tuned to the frequency of the oscillations to be amplified.

45 18. A circuit for the frequency-transformation of electrical oscillations of ultra-high frequency, comprising a discharge tube provided in the order named with at least a cathode, an oscillator grid, a space charge grid, a signal control grid and an anode, a circuit tuned to the frequency of a local oscillator connected to the oscillator grid, a circuit tuned to the frequency of the received oscillations connected to the signal grid, a circuit tuned to the difference frequency connected to the anode, two separate supply conductors connected to the space charge grid, means

50 for connecting the space charge grid for high-frequency via one of said conductors and the tuned input circuit to the signal control grid, means for connecting the space charge grid for high-frequency via the other of said conductors and the tuned output circuit to the anode, and means for connecting the space charge grid to the cathode via said other conductor.
